UNITED STATES PATENT OFFICE.

GEORGE ROBERT DAWNAY, OF LONDON, ENGLAND.

TILE FOR PERMANENT CENTERING TO FIREPROOF FLOORS.

SPECIFICATION forming part of Letters Patent No. 587,797, dated August 10, 1897.

Application filed June 13, 1896. Serial No. 595,486. (No model.) Patented in England April 29, 1895, No. 8,402.

To all whom it may concern:

Be it known that I, GEORGE ROBERT DAWNAY, a resident of 9 Fellbrigg Road, East Dulwich, London, in the county of Surrey, England, have invented certain new and useful Improvements in Tiles for Permanent Centering to Fireproof Floors, of which the following is a specification, reference being had to the accompanying drawings, forming a part thereof, in which similar letters of reference indicate corresponding parts.

This invention relates to fireproof floors and ceilings; and the object thereof is to provide improved tiles for this purpose and improved means for connecting them with the joists, beams, or girders employed for this purpose, and the invention is the same as that for which Letters Patent were granted in Great Britain April 29, 1895, No. 8,402.

The invention is fully disclosed in the following specification, of which the accompanying drawings form a part, in which—

Figure 1 is a side elevation of one of the tiles which I employ, showing the method of connecting the same with the joists, beams, or girders, which are shown in section; Fig. 2, a transverse section thereof on the line *a a*; Fig. 3, a side view of a modified form of tile; Fig. 4, a section on the line *X X* of Fig. 3; Fig. 5, a plan view of the tile shown in Fig. 3; Fig. 6, a section on the line *y y* of Fig. 3; Fig. 7, a transverse section of one of the beams, joists, or girders and showing also an end view of a number of tiles connected therewith and the method of supporting the same, the tiles shown being what are called "single-rib tiles."

In the drawings forming part of this specification I have shown at A, Fig. 1, transverse sections of two parallel joists, which are provided at their bottoms with the usual flanges C, and in the practice of my invention I provide cross bars or supports B, which rest upon these flanges, and I also provide suitable tiles T, which may be made of any suitable material and of any desired size, and which are oblong in form and of such length as to extend from one of the cross bars or supports to the other. These tiles are provided with upwardly-directed flanges or plates D, having longitudinal flanges or projections d, by means of which they are suspended from the cross

bars or supports B, and these longitudinal flanges or projections may be provided at their outer ends with depending ribs or fillets 55 *d*², which are designed to hold the tiles in proper position on the cross bars or supports B and to prevent them from being swung around, and the said tiles are so formed that when suspended from the bars or supports B 60 they will hang in proper position or be perfectly counterbalanced, so that the lower surfaces thereof may be flush or even, as shown in Fig. 7.

The bottoms of the tiles are prepared with 65 sinkings or fillets to provide proper keying facilities for plaster, cement, or other material, and the upwardly-directed plates or flanges D are formed integrally therewith, and said ribs or flanges are shorter than the body 70 portion of the tile, so as to allow of passing up clear between edges of floor bearer or joist.

The upper surfaces of the tiles are provided with longitudinal ribs G or transverse ribs *g*, as shown in Figs. 2, 3, and 4, the object of 75 these ribs being to provide proper keyings for the plaster, concrete, or other material, and these ribs are so formed when placed longitudinally as to properly counterbalance the tiles when suspended, as hereinbefore described, 80 or so that the bars or supports B will be in line with the center of gravity.

In place of providing the longitudinal ribs or fillets *d*² I may provide pegs or nails N, which will serve for a similar purpose and 85 which are passed through perforations formed in the longitudinal flanges or projections *d*.

It will be understood that any desired number of the ribs G and *g* may be employed, the only object in this connection being to provide 90 suitable devices which will serve as proper attachments for the plaster, concrete, or other material, and this is also true of the bottom surface of the tiles, or said tiles may be ornamented on their under surfaces in 95 any desired manner, and in this event no plastering is placed thereon. It will be understood, however, that projections or openings may be substituted for the ribs G and *g* and that the lower surfaces of the tiles may 100 be similarly prepared, and the hanging rods or bars B may also be made of any desired material, and my invention is not limited to the means herein described for suspending

the tiles, and any suitable device may be employed for this purpose.

Having fully described my invention, I claim as new and desire to secure by Letters

5 Patent—

1. In fireproof floors the combination with I beams or girders having upper and lower flanges, cross-bar joists engaging said flanges, tiles of an oblong form and extending from 10 one to another of said joists or beams, upwardly-directed flanges or plates secured to the said tiles, longitudinally-extending projections secured thereto, depending ribs or fillets secured to the outer ends of the said 15 projections and adapted to hold the said tile in position, said tiles being constructed so as to balance perfectly, the bottoms of said tiles being provided with sinkings, and being provided with longitudinal ribs on the upper surface 20 of said tiles, all of the said parts being combined substantially as and for the purpose set forth and described.

2. A fireproof flooring consisting of the combination of a girder B'; joists A, resting at 25 its ends upon the lower flanges of two opposite girders; cross-bars, hangers, or supports B, resting upon and against the lower flanges of two opposite joists, tiles, oblong in form and of such length as to extend from joist to 30 joist, hanging from the hangers or supports B, said tiles being provided with a perpen-

dicular flange D, having longitudinal lips or flanges d, which are provided on their outside and under edge with a thickening or fillet d², said tiles being provided with a roughening or keying surface on its bottom, for plaster, cement or the like, substantially as described.

3. A fireproof flooring consisting of the combination of a girder B', joists A, resting at 40 its ends upon the lower flanges of two opposite girders, cross-bars, hangers or supports B, resting upon and against the lower flanges of two opposite joists, tiles, oblong in form and of such length as to extend from joist to 45 joist, hanging from the hangers or supports B, said tiles being provided with a perpendicular flange D, having longitudinal lips or flanges d, which are provided on their outside and under edge with a thickening or fillet d², said tiles being provided with a smooth, finished, glazed, embossed and ornamental surface on its bottom, substantially as described.

In testimony that I claim the foregoing as 55 my invention I have signed my name, in presence of the subscribing witnesses, this 16th day of May, 1896.

GEORGE ROBERT DAWNAY.
